COMBINED BOOT-JACK AND BOOT HOOK

Filed Sept. 4, 1946

UNITED STATES PATENT OFFICE

2,571,447

COMBINED BOOTJACK AND BOOT HOOK

Charles G. Hilton, Amarillo, Tex.

Application September 4, 1946, Serial No. 694,723

7 Claims. (Cl. 223—115)

1

This application is a continuation-in-part of my prior application on Combined Boot Jacks and Boot Hooks, filed August 12, 1943, Serial No. 498,349, and now matured into Patent No. 2,408,640, dated October 1, 1946.

This invention relates to improvements in combined boot jacks and boot hooks of the character used for applying and removing the boots of individuals.

Boot jacks and boot hooks as used heretofore generally have required separate instruments for the respective purposes and have not been so constructed as to provide one instrument to serve both purposes.

The object of this invention is to improve the construction of boot jacks and boot hooks to enable these to be combined in one instrument capable of use for the respective purposes and sufficiently sturdy and rigid to remove the boots effectively when desired as well as to apply the boots by drawing them onto the feet.

A further object of the invention is to improve the construction of boot jacks and boot hooks so they will be capable of serving both purposes, and yet the separate elements forming the boot hooks are adapted to be fitted together in coacting relation to serve as a boot jack or separated and nested together for shipping and storing.

These objects may be accomplished according to certain embodiments of the invention by the provision of separate elements each of which is constructed with a boot hook thereon capable of use in drawing on the boots, and yet the elements are constructed for interengagement in coacting relation to form a boot jack that will be useful in removing a boot. The elements are interconnected as by means of a hook and eye or other provision to prevent them from collapsing when assembled to form the boot jack. Such a construction may be made sufficiently sturdy and rigid to be effective for the purpose, and yet may be separable and nested together for shipping and storing.

Certain embodiments of the invention are set forth in the accompanying drawings in which:

Fig. 1 is a perspective view of the device used as a boot jack;

Fig. 2 is a side elevation of one of the elements of the device used as a boot hook;

Fig. 3 is a bottom plan view of the device with the parts assembled as a boot jack;

Fig. 4 is a cross section therethrough on the line 4—4 of Fig. 3;

Fig. 5 is a similar view on the line 5—5 of Fig. 3;

Fig. 6 is a similar view on the line 6—6 of Fig. 3;

Fig. 7 is a side elevation of the device used as a boot jack.

Referring to the form of the invention shown in Figs. 1 to 7, the device is constructed of separable main body members 1 and 1' which may be formed of wood or other suitable supporting

2

material that has sufficient light weight and sturdiness for the purpose. These body members 1 and 1' are elongated and adapted to be fitted together in side by side relation as shown in Figs. 1, 3 and 5 where they may be secured by hook and eye members 2 and 3 attached to the underside thereof as shown in Figs. 3 and 5.

Each of the body members 1 and 1' has a laterally tapered yoke arm 4 on one end thereof, which arms 4 cooperate to form a yoke when the members 1 and 1' are assembled in side by side relation, which yoke is used as a boot jack for removing the boot as shown in Fig. 7. The inner face of this yoke is covered with a cushioning material such as soft leather, indicated at 5, to prevent marring of the heel portion of the boot during removal thereof.

The body members 1 and 1' are adapted to be supported in the inclined positions indicated in Figs. 1 and 7 when used as a boot jack by stands 6 at the undersides thereof. These stands are shown as formed by metal rods extending lengthwise under the body members. At one end, each of the stands has an upturned portion 7, which extends into an opening at the underside of the body members 1 and 1' and is secured thereto by a nail 8. At the opposite end, each stand 6 has an outturned boot hook 9 so disposed as to lie in longitudinal alignment with the body member 1 or 1' and when these members are assembled in side by side relation, the hooks 9 project in opposite directions from each other and are disposed at the ends of the body members to form a lateral brace for the boot jack to prevent tipping thereof. Each of the stands has the shank portion thereof extending through a groove 10 formed in the undersurface of the body member 1 or 1' whereby the undersurfaces of these body members will abut the floor without interference by the rods forming the stands. Each rod may be provided with a serrated top surface at the point of engagement with the bottom of the groove 10 to prevent relative slippage therebetween. These rods may be secured to the body members as by staples 8', which embrace the rods and are driven into the undersurface of the body members as shown in Figs. 3 and 4.

The body members have bevelled upper inner edges cooperating to form a groove 10' therebetween when these members are assembled in side by side relation and used as a boot jack. Such a groove will prevent pinching of the skin of the foot between the members when assembled in this relation and held by the bare foot while removing a boot from the other foot.

When the members 1 and 1' are fitted together as shown in Figs. 1 and 7, they cooperate to form a boot jack which may be used to remove a boot as indicated in dotted lines in Fig. 7. One foot holds the stand in secure position on the floor while the heel portion of the boot on the other foot is engaged in the yoke formed by the arms 4 for drawing the boot off the foot. The mutually

inwardly facing sides of these yoke arms converge downwardly and inwardly so as to form a wedging yoke that will engage the spur portion of the boot heel to hold the boot effectively while the foot is withdrawn therefrom. The hook and eye connections 2 and 3 beneath the boot jack serve to prevent collapsing thereof during this operation. The offset engaging ends of these elements 2 and 3 permit the body members 1 and 1' to fit together in complementary relation presenting substantially a flat top surface on the boot jack so that it may be held in place effectively in use.

These body members may be separated from each other and used respectively as boot hooks as shown in Fig. 2, being of a size and shape that they may be grasped readily by the user either at the sides of the body members 1 and 1' or by the offset ends 1 of the stands, which will form handles for the purpose. By constructing the stand and the hook 9 as one integral unit, the line of pull is lengthwise of the member and in alignment with the corresponding loop on the boot. This makes it possible to use a smaller size of rod for the purpose than if this rod were offset or deformed, which also reduces the cost of the device and makes it lighter in weight both for use and shipping.

The interconnection of the respective members 1 and 1' not only enables these members to be separated readily for use as boot hooks, but these members may be separated and nested together for shipping and storage, because they may be packed effectively to reduce their size and capacity.

While the invention has been illustrated in a certain embodiment, it is recognized that variations and changes may be made therein without departing from the invention except as specified in the claims.

I claim:

1. A combined boot jack and boot hook comprising a pair of elongated members, each of said members having a yoke arm on one end thereof, said yoke arms being adapted to cooperate to form a boot jack when the members are assembled in side by side relation, means detachably connecting said members together in side by side relation, means forming a supporting stand for holding the connected members in inclined positions as a boot jack said stand-forming means also including means which form hooks which extend laterally in opposite directions from said members at the respective ends of the latter which are opposite to the ends where the yoke arms are disposed, said hooks being positioned in a horizontal plane so as to form a level support for said members in their inclined positions.

2. A combined boot jack and boot hook comprising a pair of elongated body members arranged in side by side relation, and each of said members having a wide top surface and constructed at one end with a yoke arm adapted to cooperate with the yoke arm on the complementary member to form a boot jack, a stand connected with the body members intermediate the ends thereof for holding the body members in upwardly inclined positions in side by side relation, said stand also including means which form hooks which extend laterally in opposite directions from said members at the respective ends of the latter which are opposite to the ends where the yoke arms are disposed, said hooks being positioned in a horizontal plane so as to form a level support for said members in their inclined positions.

3. A combined boot jack and boot hook comprising a pair of elongated body members arranged in side by side relation, and each of said members having a wide top surface and constructed at one end with a yoke arm adapted to cooperate with the yoke arm on the complementary member to form a boot jack, a hook connected with each body member at the opposite end thereof and a portion thereof extending forward to form a stand which is connected with the body members intermediate the ends thereof for holding the body members in upwardly inclined positions in side by side relation, and hook and eye connections between the body members for detachably securing said members together.

4. A combined boot jack and boot hook comprising elongated body members arranged in side by side relation and having yoke arms at one end thereof cooperating to form a boot jack, means detachably connecting said members together, and a stand on each member secured thereto and having a portion thereof forming a boot hook.

5. A combined boot jack and boot hook comprising elongated body members arranged in side by side relation and having yoke arms at one end thereof cooperating to form a boot jack, means detachably connecting said members together, and a stand secured to each member in substantial longitudinal alignment therewith and providing a support therefor, said stand having a portion thereof forming a boot hook at one end of the member.

6. A combined boot jack and boot hook comprising elongated body members arranged in side by side relation and having yoke arms at one end thereof cooperating to form a boot jack, means detachably connecting said members together, and a stand on each member secured thereto and having a portion thereof forming a boot hook, said stand including a rod having an offset end secured to the member and having the hook formed integral with the opposite end of said rod.

7. A combined boot jack and boot hook comprising elongated body members arranged in side by side relation and having yoke arms at one end thereof cooperating to form a boot jack, means connecting said members in said side by side relation but affording ready separation of the members, and a stand on each member secured thereto and having a portion thereof forming a boot hook, said stand including a rod extending substantially lengthwise of the member and having an offset end secured to the member at an angle thereto and having the opposite end of said rod formed integral with the hook, said member having a groove therein in which the rod is disposed at a point adjacent the hook.
